TUNNEL LINING STRUCTURE AND GAUGE
THEREFORThomas L. White, Youngstown, Ohio, assignor to
The Commercial Shearing & Stamping Co.,
Youngstown, Ohio, a corporation of Ohio

Application March 3, 1947, Serial No. 731,955

7 Claims. (Cl. 61—45)

1

This invention relates generally to the construction of linings for subterranean bores and, in particular, to a gage adapted to hold a cylindrical lining composed of successive courses of segments to the desired transverse diameter.

In boring shield-driven tunnels, the soil adjacent the bore is seriously disturbed from its normal condition by the passage of the shield. Until final settlement has occurred, therefore, there is a resulting tendency to ready movement which may cause distortion of the lining from the desired circular section. This tendency is increased because of the impossibility of wholly filling the space between the lining and the bore through which the shield travels, by pumping fluid concrete through holes in the lining in accordance with the usual practice. The lining is also subject to slight sagging under its own weight. Attempts have been made to prevent distortion of tunnel linings by pulling the sides together with cables or, in small tunnels, by using vertical jacks. The former practice is very troublesome and inaccurate and can resist force in only one direction. The latter is impractical because it interferes seriously with freedom of movement along the tunnel adjacent the working face and also can resist force in one direction only. Furthermore, these tunnels are usually of such size as to require a platform on which the work of tightening bolts, grouting, caulking, welding or other operations may be performed on the upper portion of the ring by the workmen. Such a platform requires some substantial support in order to provide a safe working floor.

I have invented a novel gage for holding tunnel linings to the desired transverse diameter and thus accurately maintaining the circular sectional shape thereof. In a preferred embodiment, my gage comprises a head or block having a pair of cooperating jaws at one end adapted to hook onto a portion of the lining, and a beam or shank extending from the other end of the head or block and having similar jaws at its end adapted to hook onto another portion of the lining substantially diametrically opposite the portion engaged by the jaws on the head. I provide means for adjusting the head and shank toward and from each other to apply controlled tension, thereby holding the lining precisely to the desired diameter. I employ a substantial number of my improved gages, say approximately forty, for the usual width of liner segments (2½ ft.), and apply one gage to each course of segments erected as the bore is extended. I leave the gages in position until the bore has been advanced a suitable distance, say 100 ft., allowing sufficient time for any settlement of the soil behind the shield. The gages are then successively removed from the rear of the line and moved forward to

2

the last course of segments erected. The gages are preferably installed in horizontal position and may serve as beams to support a working deck of suitable planking laid thereon.

5 A complete understanding of the invention may be gained from the following detailed description and explanation and by reference to the accompanying drawings illustrating a present preferred embodiment. In the drawings,

10 Figure 1 is a cross section through a tunnel lining showing a gage in accordance with my invention installed therein;

15 Figure 2 is an elevation of the gage to enlarged scale with one end in central vertical section and a portion broken away;

20 Figures 3, 4 and 5 are transverse sections through the gage taken along the planes of lines III—III, IV—IV and V—V, respectively; and

25 Figure 6 is a partial perspective view showing one end of the gage.

Referring in detail to the drawings, a tunnel lining indicated generally at 10 comprises two identical arcuate liner plates or segments 11 assembled end-to-end with a third arcuate liner plate or segment 13 and a key 14 to form a complete ring, a plurality of such rings being disposed side-by-side to form the complete lining. The arcuate segments are fabricated from metal plate and structural members. Each ring includes circumferential flanges 15, segment junction flanges 16, a circumferential skin plate 17 and axially extending flanged cross bars or struts 18, the flanges 15 and skin plate 17 being integrally connected to each other and welded to the bars 18. The gage or cross brace of my invention is indicated generally at 19. As shown in Figure 1, it engages the cross bars 18 on the horizontal diameter of the cross section of the lining.

30 Referring now more particularly to Figures 2 through 4 for a detailed description of the gage, it will be observed that the device comprises a head or block 20 and a beam or shank 21 extending in alinement therewith. The beam includes a tube 22 of square section and an extension 23 of similar shape telescoping therein. The tube and extension are provided with holes, one of which is shown at 24, and a removable locking pin 25 whereby the extension may be secured in the desired position relative to the tube.

35 A fixed jaw or hook member 26 is secured to the outer end of the extension 23. The hook member is let into the end of the extension. The top wall of the extension is cut away and the sides are notched to receive the jaw. Cheek plates 27 are pivoted to the end of the extension on a pin 28. A movable jaw or hook member 29 is welded between the cheek plates on the opposite side of the central axis of the beam 21 and extension 23

from the other jaw 26. This jaw extends upwardly above the lower edges of the plates. The bottom and side walls of the extension are cut away as at 31 to clear the portion of the hook member between the cheek plates. A removable locking pin 30 is adapted to be inserted through aligned holes in the cheek plates and extension 23 to hold the movable jaw in closed position as illustrated. When the pin 30 is pulled out, the jaw 29 opens permitting the jaw 26 to be disengaged from the cross bar 18. A spacer plate 32 extends between the side walls of the extension above the portion cut away at 31. It will be apparent that, so long as the jaws 26 and 29 are closed, they are capable of exerting a heavy tension on the cross bar 18 which is transmitted directly to the ring of the lining composed of segments 11 through 14. Abutment plates 32a and 32b (Figures 1 and 6) are secured to the respective outer ends of the head 20 and extension 23 to abut the flanged portion of the cross bars 18 held between the corresponding adjacent pair of jaws in order to prevent the cross bars 18 from moving substantially toward each other.

The head or block 20 is fabricated from plate and includes side walls 33 and 34 and a top wall 35. A fixed jaw 36 is let into the top wall and welded to the side walls. Cheek plates 37 are pivoted to the side walls 33 and 34 on a pin 38. A movable jaw 39 is disposed between and secured to the cheek plates 37 in the same manner as the jaw 29 is mounted on the plates 27. As shown in Figure 1, the jaws 36 and 37 engage one of the cross bars 18 diametrically opposite that engaged by the jaws 26 and 29. The jaw 39 is held in operative relation with the jaw 36 by a removable pin 40 inserted through holes in the cheek plates and side walls of the block. A split sleeve composed of mating upper and lower halves 41 and 42 is disposed between the side walls 33 and 34 adjacent the inner end thereof. The upper half 41 of the sleeve is welded to the side walls. The lower half is removably secured thereto by bolts 43. The fixed jaws 26 and 36, and the other jaws 29 and 39 when in locked position, are adapted to abut the adjacent portions of the skin plates 17 and to oppose further movement of such portions toward each other if the skin plates should become forced against the projecting ends of the jaws.

The upper and lower halves 41 and 42 forming the split sleeve are bored to provide a bearing for a shaft 44. The shaft has a thrust-sustaining collar or flange 45 engaging the outer end of the sleeve. The other end of the sleeve is threaded as at 46 and is turned into a nut 47 seated in the adjacent end of the tube 22. A hub 48 is mounted on the shaft between the head 20 and shank 21 and is provided with capstan bars 49 whereby the shaft may be turned to adjust the head and shank toward or from each other. It is thus a simple matter to maintain the desired distance between the cross bars engaged by the jaws 26, 29 and 36, 39.

As already indicated, I employ a substantial number of gages to maintain the desired horizontal diameter of the lining courses until the surrounding soil has had an opportunity to settle or the concrete shell surrounding the lining has set and attained its full strength. Ordinarily, it will be desirable to use gages on the last 100 ft. of the lining erected. As successive courses are erected at the working face, gages are taken down from the rear of the line brought forward and set up in the course last erected. The gages

may readily be disconnected and transported through the lining by pulling out the pins 25, 30 and 40, after backing out the screw shaft 44 slightly from the nut 47. The two latter pins release the jaws. The removal of pin 25 permits the extension 23 to be telescoped in the tube 22, facilitating handling of the gage. When transported to the working face, the gage may easily be reinstalled by pulling out the extension, inserting the pin 25, closing the jaws on the cross bars on the horizontal diameter, inserting the pins 30 and 40 and turning the shaft 44 to draw the sides of the lining inwardly or outwardly to the extent necessary to establish the desired diameter. The overall design of the gage is preferably such that the hub 48 engages nut 47 when the jaws have been drawn together sufficiently to fix the horizontal diameter at the correct figure. As indicated in Figure 2, the fixed jaws 26 and 36 support the gage on the cross bars 18 while the jaws 29 and 39 are being opened and closed.

The gages adjacent the working face are well adapted to serve as beams supporting a working floor or deck composed of planks 50 laid thereon to facilitate access to the upper portion of the tunnel lining and to the working face.

It will be apparent from the foregoing that the invention provides simple yet effective means for maintaining the desired horizontal diameter of a tunnel lining against the normal sag due to the weight of the segments and the vertical load of the soil above the lining. The extensible tension gage permits accurate correction of any departure from the proper horizontal diameter. The gages are effective not only to apply the desired tension but also to resist thrust which in some installations results from lateral pressure in excess of the vertical load on the lining. The gages may be readily set up, taken down or transported. They are of simple yet sturdy construction and may be made at relatively small cost. They may be easily manipulated by unskilled labor and are not subject to being damaged very readily even under the severe service conditions encountered in tunnel excavation. The gages are also of advantage in supporting planks adjacent the working face to afford a deck capable of carrying a grout machine and other apparatus used in tunnel construction.

Although I have illustrated and described but a preferred embodiment of the invention, it will be recognized that changes in the details of construction disclosed may be made without departing from the spirit of the invention or the scope of the appended claims.

I claim:

1. A tunnel-liner cross brace and gage comprising an elongated body, screw means to adjust the length of said body, a pair of coacting hooked jaws extending from each of the opposite ends of the body, one of each pair of jaws being mounted on the body for movement toward and from the fixed jaw, each pair of jaws when in closed position being disposed on opposite sides of the central axis through the body and being hooked toward said axis, with the fixed jaws on the same side of the axis, whereby the fixed jaws are adapted to rest on adjacent parts of a tunnel-lining structure to support the brace while the movable jaws are being opened and closed, and means for releasably holding the movable jaws in closed position, whereby when the jaws are closed on a pair of spaced flanged parts of a tunnel-lining structure the jaws hold the parts against relative separation, and the screw means are op-

erable to draw the parts together to align the structure.

2. A tunnel-liner cross brace and gage comprising an elongated body adapted to withstand tension and compression, screw means to adjust the length of said body, a pair of coacting hooked jaws extending from each of the opposite ends of the body, one of each pair of jaws being rigidly fixed to the body and the other of each pair of jaws being mounted on the body for movement toward and from the adjacent fixed jaw, each pair of jaws when in closed position being disposed on opposite sides of the central axis through the body and being hooked toward said axis, with the fixed jaws on the same side of the axis, whereby the fixed jaws are adapted to rest on adjacent parts of a tunnel-lining structure to support the brace while the movable jaws are being opened and closed, means for releasably holding the movable jaws in closed position, and abutment means at opposite ends of the body spaced inwardly of and adjacent the hooked portions of the corresponding pair of jaws when the jaws are closed, whereby when the jaws are closed on a pair of spaced flanged parts of a tunnel-lining structure the said parts are restrained against movement away from each other by the closed jaws and are restrained against movement toward each other by the abutment means.

3. A tunnel-liner cross brace and gage comprising an elongated body, a pair of coacting hooked jaws extending from each of the opposite ends of the body, one of each pair of jaws being mounted on the body for movement toward and from the fixed jaw, each pair of jaws when in closed position being disposed on opposite sides of the central axis through the body and being hooked toward said axis, and means for releasably holding the movable jaws in closed position, said body including screw means to adjust the length of the body and being formed in two major portions axially slidable one within the other with alignable openings through the respective portions for receiving a pin to lock the two portions of the body together, whereby the brace and gage is readily telescoped for transportation in a tunnel and is readily extended, clamped on a pair of spaced flanged tunnel-liner parts, and adjusted in length to control the spacing of said tunnel-liner parts.

4. A tunnel-liner cross brace and gage comprising an elongated body adapted to withstand tension and compression, a pair of coacting hooked jaws extending from each of the opposite ends of the body, one of each pair of jaws being rigidly fixed to the body and the other of each pair of jaws being mounted on the body for movement toward and from the adjacent fixed jaw, each pair of jaws when in closed position being disposed on opposite sides of the central axis through the body and being hooked toward said axis, with the fixed jaws on the same side of the axis, whereby the fixed jaws are adapted to rest on adjacent parts of a tunnel-lining structure to support the brace while the movable jaws are being opened and closed, means for releasably holding the movable jaws in closed position, and abutment means at opposite ends of the body spaced inwardly of and adjacent the hooked portions of the corresponding pair of jaws when the jaws are closed, said body including screw means to adjust the length of the body with stop means to halt adjustment of the screw means at a predetermined length of the body, and said body being formed in two

major portions axially slidable one within the other with alignable openings through the respective portions for receiving a pin to lock the two portions of the body together, whereby the brace and gage is readily telescoped for transportation in a tunnel and is readily extended, clamped on a pair of flanged tunnel-liner parts, and adjusted to a predetermined length to control the spacing between said tunnel-liner parts.

5. Lining structure for a generally horizontal, circular tunnel, comprising a substantially cylindrical metal skin extending generally horizontally within a tunnel bore, a series of spaced structural rings extending circumferentially against the inner surface of the skin, a series of axially extending flanged bars secured to the inner surface of the skin and to the rings, including a pair of such bars between at least a pair of the metal rings disposed at about the level and on opposite sides of the adjacent portion of the cylindrical axis of the skin, and a cross brace connecting said pairs of bars, said cross brace having releasably locked pairs of jaws at its opposite ends gripping the connected pair of bars and having screw means to extend and contract its length, whereby the cross brace is readily and firmly attachable and is adjustable to control distortion of the skin.

6. Lining structure for a generally horizontal, circular tunnel, comprising a substantially cylindrical metal skin extending generally horizontally within a tunnel bore, a series of spaced metal rings extending circumferentially against the inner surface of the skin, a series of axially extending flanged bars secured to the inner surface of the skin and to the rings, some of said bars being disposed in pairs at about the level and on opposite sides of the cylindrical axis of the adjacent portion of the skin, and a series of cross braces connecting said pairs of bars, each cross brace having two body portions, which portions are connected by lengthwise-extending screw means for adjustment of the length of the cross brace while retaining rigidity of the cross brace against transverse bending, which portions each terminate in an integral fixed jaw overlying a flanged portion of one of the pair of bars connected by the cross brace, and which portions each mount a releasably locked jaw gripping the opposite side of the bar engaged by the integral jaw, whereby the cross braces are readily and firmly attachable, are adjustable to correct distortion of the skin, and provide a firm and safe foundation for temporary flooring in the tunnel.

7. The apparatus of claim 6 with a flooring of planks laid across the cross braces.
